Primary Examiner — Bao-Yen T Nguyen*Assistant Examiner* — Jessica Ruth Grable(74) *Attorney, Agent, or Firm* — Thedford I. Hitaffer; Hitaffer & Hitaffer, PLLC(57) **CLAIM**

The ornamental design for a bed end, as shown and described.

DESCRIPTION

FIG. 1 is a front perspective view of a bed end.

FIG. 2 is a front elevational view thereof.

FIG. 3 is a rear elevational view thereof.

FIG. 4 is a top plan view thereof.

FIG. 5 is a right side elevational view thereof; and,

FIG. 6 is a left side elevational view thereof.

The broken lines represent portions of the bed end and form no part of the claimed design.

1 Claim, 4 Drawing Sheets(56)
